UNITED STATES PATENT OFFICE.

GUSTAVE H. DWORZEK, OF SAN FRANCISCO, CALIFORNIA.

AUTOMATIC ROLL-PAPER-PRINTING DEVICE.

SPECIFICATION forming part of Letters Patent No. 723,517, dated March 24, 1903.

Application filed January 2, 1903. Serial No. 137,464. (No model.)

To all whom it may concern:

Be it known that I, GUSTAVE H. DWORZEK, a citizen of the United States, residing in the city and county of San Francisco, State of California, have invented an Improvement in Automatic Roll-Paper-Printing Devices; and I hereby declare the following to be a full, clear, and exact description of the same.

My invention relates to an apparatus for printing the names, advertisement, or other matter upon roll-paper such as is employed for wrapping packages and the like.

It consists of a mechanism actuated in unison with the revolution of the roll, whereby a single impression is printed upon the roll during the first revolution of the roll-carrier, and the mechanism is then disengaged, so that any desired amount of paper may thereafter be taken from the roll without further imprint being made.

It also comprises details of construction which will be more fully explained by reference to the accompanying drawings, in which—

25 Figure 1 is an end view of my apparatus, with section showing the printing and disengaging mechanism. Fig. 2 is a rear view of the same. Fig. 3 is a sectional view of disengaging-gears. Fig. 4 is a plan view of same.

30 A is a standard or support of any suitable description, in which is journaled a drum carrying a roll of paper 2.

35 3 is a fulcrumed swinging frame in which the printing and automatically-disengaging mechanism is carried. This frame may be placed in any desired relation with the paper-roll. I have here shown it as suspended above the upper and rear portion of the roll, so that it will swing down by gravitation or 40 by a spring, if desired, so that the printing-wheel will rest against the surface of the paper. This wheel has a portion of its surface, as 4, carrying the type or character to be printed; and the other portion 4^a of its circumference is blank. It is the object of my 45 invention to cause this printing-wheel to make a single revolution when the paper is drawn off the main roll 2, and thus make a single imprint upon the paper, after which 50 the revolution of the printing-roll is arrested, and it remains with the blank portion 4^a pre-

sented to the paper-roll, so that no further printing will take place, however much paper may be removed from the roll.

55 5 represents an ink-pad, which is properly supported to roll against the type or character surface and keep it properly supplied with ink.

6 and 6^a represent blotting-rolls to prevent any blur by a surplus of ink upon the type 60 or the paper after the latter is printed.

In the present case I have shown the blotter 6^a journaled in a supplemental frame 7, which may be acted upon by a spring or gravitation, so as to rest against the main paper- 65 roll.

The printing-roll 4^a is loosely mounted upon a shaft 8, journaled in the frame 3 and extending parallel with the paper-roll 2. Upon this shaft are fixed disks 9, which contact with the periphery of the paper-roll, and these disks and the shaft are caused to rotate whenever the paper is pulled off and the paper-roll is revolved. This revolution is communicated to the printing-roll as follows: 75 The printing-roll is loosely mounted and turnable upon the shaft 8, and upon this shaft is fixed a toothed or escapement wheel 10. A spring-pressed pawl 11 is carried by the printing-roll and when free is adapted to engage 80 with the toothed wheel 10, so that the rotation of the shaft and the toothed wheel is imparted to the printing-roll as long as the pawl 11 is in engagement with the toothed wheel. This enables the toothed wheel to turn the 85 printing-roll in unison with the movement of the latter and sufficiently to bring the type-surface into contact with the paper during its revolution. It is then desirable to stop the revolution of the printing-roll, and this is effected by means of an arm 12, fixed in such 90 position with relation to the pawl 11 that when the printing-roll has made a semirevolution the pawl will come in contact with the arm and will be disengaged from the toothed 95 wheel 10. This causes the printing-roll to stop its revolution, while the paper-roll may continue to revolve without producing further action upon the printing-roll.

100 Whenever the desired amount of paper has been removed from the printing-roll, it is necessary to again place the printing-roll in con-

dition to be revolved and to again print upon the roll when another section of paper has to be removed therefrom. I have therefore devised a disengaging device by which the 5 pawl 11 is disengaged from the holding-arm 12 and allowed to again drop into engagement with the teeth of the wheel 10. This device consists of a train of gearing 13, which is mounted in the frame 14, and this frame 10 is pivoted on a shaft 15, which carries a gear-wheel 16, forming a part of the train of gearing here shown. The shaft 8 either carries a pinion or has teeth formed upon it, as shown at 17, so that when the shaft 8 is being re- 15 volved it communicates motion to the gear-wheel 16 and through it to the train in the frame. The train of gears acts upon an escapement 18, by which its oscillation controls the revolution of the train of gearing, 20 so that as the paper is being pulled off the roll the revolution of the paper-roll being communicated through the rollers 9 to the shaft 8 will revolve the train of gearing; but as the escapement prevents this train from 25 moving freely it will be obvious that the pinion 17 will carry the wheel 16, with which it is engaged, around with it, thus causing the frame 14 to turn upon its pivot-shaft and to climb up around the shaft 8 as long as any 30 paper is being pulled off the roll. As soon as the revolution of the paper-roll ceases the weight of the frame 14 is sufficient to cause it to drop back to its normal position. This frame 14 has a lug 20, so placed as to engage 35 a pivoted latch 21, carried by an arm 22, projecting from the printing-wheel, and when the weighted frame 14 strikes this latch it does so with sufficient force to disengage the pawl 11 from the holding-arm 12, thus allowing 40 the pawl 11 to again fall into engagement with the wheel 10 and to be in readiness to again turn the printing-wheel when the paper-roll is revolved. It will thus be seen that the first movement of revolution of the paper- 45 roll communicates motion through the wheels 9, the shaft 8, the toothed wheel 10, and the engaging pawl 11 to revolve the printing-wheel a sufficient portion of a revolution to print its characters upon the surface of the 50 paper.

I have here shown the printing-wheel as being capable of a full revolution, at the end of which the pawl 11, striking the arm 12, is disengaged from the toothed wheel, and any 55 further revolution of the paper-wheel will have no effect upon the printing-roll. While this is going on the pinion 17 of the shaft 8, engaging the escapement-gear mounted in the frame 14, lifts the latter, turning about 60 its fulcrum-shaft by reason of the impeding action of the escapement, and causes the frame 14 to swing upward and to continue to be lifted in this manner as long as paper is being removed from the roll. As soon as the 65 roll ceases to revolve the weight of the frame 14 and the train carried by it causes it to drop back to its normal position, and when it

reaches its lowest point it strikes the latch 21, which is carried by the printing-wheel, with sufficient force to cause the pawl 11 to 70 be disengaged from the arm 12 and to again fall into engagement with the toothed wheel 10. The latch 21 is pivoted and spring-pressed, so that it allows the disengaging-arm 20 of the frame 14 to pass it in one direction 75 by the yielding of the spring and to remain rigid against movement in the opposite direction, so that it will act to disengage the latch of the printing-wheel.

Having thus described my invention, what 80 I claim, and desire to secure by Letters Patent, is—

1. The combination with a revoluble paper-carrying roll of a yielding frame, a shaft journaled therein, with fixed rollers adapted to 85 contact with the paper-roll, a toothed wheel also fixed to the shaft, a printing-roll loosely turnable upon the shaft, a pawl carried by the printing-roll adapted to engage the toothed wheel whereby motion is transmitted to 90 revolve the printing-roll, and a mechanism for disengaging the pawl after the printing has been completed.

2. The combination with a revoluble paper-carrying roll of a yielding frame, a shaft journaled therein with rollers adapted to contact with the paper-roll and transmit motion to the shaft, a printing-roll loosely turnable upon the shaft having a pawl carried upon it, a toothed wheel fixed upon the shaft with which 100 wheel the pawl engages to transmit motion to the printing-roll and an arm by which the pawl is disengaged from the toothed wheel and the printing-wheel held stationary after a single revolution.

3. The combination with a revoluble paper-carrying roll of a shaft journaled in a yielding frame, with rollers contacting with the paper-roll and transmitting motion to the shaft, a toothed wheel fixed upon the shaft, a 110 printing-roll loosely turnable upon the shaft, a pawl carried by the printing-roll engaging the toothed wheel to transmit motion to the printing-roll, an arm by which the pawl is disengaged and the printing-roll stopped after 115 each revolution, and a mechanism movable by the revolution of the shaft and acting to release the pawl and allow it to again engage the toothed wheel after the revolution of the paper-roll has ceased.

4. The combination with a revoluble paper-carrying roll of a shaft journaled in a yielding frame having rollers fixed thereon and contacting with the paper-roll to transmit motion to the shaft, a toothed wheel fixed to 125 and revoluble with the shaft, a printing-roll loosely turnable upon the shaft, a pawl by which the printing-roll is connected with the toothed wheel, an arm by which the pawl is disengaged from the toothed wheel after a 130 single revolution of the printing-roll to stop the latter, a train of gearing and an escapement and fulcrumed frame in which it is carried, a pinion upon the revoluble shaft en-

gaging one of the gear-train whereby the latter and the frame are raised about the fulcrum during the revolution of the shaft and adapted to fall by gravitation when said revolution ceases, an arm carried by the printing-roll and a latch projecting so as to be struck by the descending frame whereby the holding-pawl of the printing-wheel is released

and allowed to engage the toothed driving-wheel.

In witness whereof I have hereunto set my hand.

GUSTAVE H. DWORZEK.
